US00D882768S

(12) **United States Design Patent** (10) **Patent No.:** **US D882,768 S**
(45) **Date of Patent:** ** *Apr. 28, 2020

(54) **URINE COLLECTION DEVICE**

(71) Applicant: **SAGE PRODUCTS, LLC**, Cary, IL (US)

(72) Inventors: **Brett Blabas**, Cary, IL (US); **Kristin M. Sexton**, Cary, IL (US); **Ryan A. Alvarez**, Chicago, IL (US)

(73) Assignee: **SAGE PRODUCTS, LLC**, Cary, IL (US)

(*) Notice: This patent is subject to a terminal disclaimer.

(**) Term: **15 Years**

(21) Appl. No.: **29/616,869**

(22) Filed: **Sep. 8, 2017**

(51) LOC (12) Cl. **24-02**

(52) U.S. Cl.

USPC **D24/122**

(57) **CLAIM**

We claim the ornamental design for a urine collection device, as shown and described.

DESCRIPTION

FIG. 1 is a front, bottom perspective view of the claimed design of the urine capture device;

FIG. 2 is a front, top perspective view of the claimed design of FIG. 1;

FIG. 3 is a rear, bottom perspective view of the claimed design of FIG. 1;

FIG. 4 is a rear, top perspective view of the claimed design of FIG. 1;

FIG. 5 is a bottom view of the claimed design of FIG. 1;

FIG. 6 is a top view of the claimed design of FIG. 1;

FIG. 7 is a left side view of the claimed design of FIG. 1;

FIG. 8 is a right side view of the claimed design of FIG. 1;

FIG. 9 is a front side view of the claimed design of FIG. 1; and,

FIG. 10 is a rear side view of the claimed design of FIG. 1. The broken lines in the drawings are for illustrative purposes only and form no part of the claimed design.

1 Claim, 8 Drawing Sheets
